(57) **CLAIM**

The ornamental design for a crib, as shown and described.

DESCRIPTION

FIG. 1 is an upper perspective view showing my new design
for a crib.

FIG. 2 is a lower perspective view thereof.

FIG. 3 is front side plan view thereof, the back side being a
mirror image.

FIG. 4 is a right side plan view thereof, the left side being a
mirror image.

FIG. 5 is a top side plan view thereof; and,

FIG. 6 is a bottom side plan view thereof.

The broken lines adjacent the shaded areas represent the
boundaries of the claimed design, while the other broken lines
representing the outline of portions of the crib depict environ-
mental subject matter only, and form no part of the
claimed design.
